UNITED STATES PATENT OFFICE

JAMES C. BARBETTI, OF VINELAND, NEW JERSEY

NECKWEAR

Application filed December 30, 1932. Serial No. 649,615.

The present invention appertains to new and useful improvements in the general art of apparel and more particularly to a necktie of the made-up type.

5 The principal object of the present invention is to provide a necktie having all the general appearances of a hand made-up tie, wherein the tie is provided with a constant knot, to the end that the knot need not be 10 reformed each time the tie is used.

Another important object of the invention is to provide a necktie structure wherein the front and tail pieces thereof are not disturbed in adjusting the tie for use.

15 Various other important objects and advantages of the invention will become apparent to the reader of the following specification.

In the drawing:

20 Figure 1 represents a rear elevational view of the necktie with the tail member spread open to disclose the free end of the neck encircling band.

25 Figure 2 represents a fragmentary rear elevational view of the tie with the parts intact.

Figure 3 represents a sectional view through the tail member of the tie.

30 Figure 4 represents an enlarged fragmentary detailed sectional view taken substantially on line 4-4 of Figure 2.

35 Referring to the drawing wherein like numerals designate like parts it can be seen that numeral 5 represents the face portion of the tie strip, the same being provided with a portion from which the knot structure 6 is formed. Extending from this is the neck encircling band or strap 7 which forms a loop by having its free end portion trained 40 through the knot 6 and longitudinally through the tail member 8, which tail member is secured to the lower portion of the knot at the rear side of the face portion 5 of the tie.

45 By referring to Figure 1, it can be seen that the tail member 8 is slotted longitudinally and the edge portions of the tail member at the edge portions of the slit are provided with male and female fastening members 9-10 respectively which permit the tail

member to be secured together at its edge portion as in the manner substantially shown in Figures 1 and 3.

The free end of the neck encircling strap 7 has a small stiffening member 11 such as 55 cardboard or the like placed therein so that the loop defined by the band can not be pulled apart by pulling this free end through the knot.

At this point, it will be observed that the 60 face member 5 and the tail member 8 are fixed with respect to each other and with respect to the knot structure 6 and there is no longitudinal deviation between these two members when the tie is being adjusted to 65 the neck of a wearer.

In placing the necktie for use, the tail 70 member 8 is opened up after the loop has been enlarged by pulling the free end toward the knot structure 6 and after the loop has been placed over the head and around the collar, the stiffened end of the loop, that is its free end, is gripped and pulled toward the free end of the tail member 8 and when the proper tightness of the loop has been obtained, 75 the fastening elements 9-10 can be engaged by closing the tail member 8.

Thus, the parts 5, 6 and 8 always remain 80 intact and in themselves afford no means of adjustment which would cause wrinkling or discoloration thereof.

While the foregoing specification sets forth the invention in specific terms, it is to be understood that numerous changes in the 85 shape, size and materials may be resorted to without departing from the spirit or scope of the invention as claimed hereinafter.

Having thus described my invention, what I claim as new is:

1. A made-up tie comprising a tie strip including a face and knot formed portion, said knot portion being provided with a neck encircling band portion having a free end, a tail member attached at one end to the knot, 90 said band extending at its free end portion through the knot and longitudinally in the said tail member.

2. A made-up tie comprising a tie strip including a face and knot formed portion, said knot portion being provided with a neck en- 100

circling band portion having a free end, a tail member attached at one end to the knot, said band extending at its free end portion through the knot and longitudinally in the 5 said tail member, said tail member being slit-
ted longitudinally to permit access to the interior thereof.

3. A made-up tie comprising a tie strip including a face and knot formed portion, said 10 knot portion being provided with a neck encircling band portion having a free end, a tail member attached at one end to the knot, said band extending at its free end portion through the knot and longitudinally in the 15 said tail member, said tail member being slit-
ted longitudinally to permit access to the interior thereof, means for detachably connecting the edge portions of the tail member together at the slit.
- 20 4. In a necktie, a knot structure, face and tail members fixed with respect to the knot structure and with respect to each other, and a loop strip, one end of the loop strip being fixed with respect to the knot, the other end 25 of the loop strip being disposed through the knot and into the said tail member.

In testimony whereof I affix my signature.
JAMES C. BARBETTI.
